US00D975079S

(12) **United States Design Patent** (10) Patent No.: **US D975,079 S**
(45) Date of Patent: ** *Jan. 10, 2023

(54) **ELECTRONIC DEVICE**(71) Applicant: **Apple Inc.**, Cupertino, CA (US)(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendörfer**, San Francisco, CA (US)(73) Assignee: **Apple Inc.**, Cupertino, CA (US)

(*) Notice: This patent is subject to a terminal disclaimer.

(**) Term: **15 Years**(21) Appl. No.: **29/699,061**(22) Filed: **Jul. 23, 2019****Related U.S. Application Data**

(60) Continuation of application No. 29/585,673, filed on Nov. 28, 2016, now Pat. No. Des. 860,218, which is a continuation of application No. 29/455,071, filed on May 16, 2013, now abandoned, which is a continuation of application No. 29/406,040, filed on Nov. 9, 2011, now Pat. No. Des. 684,581, which is a division of application No. 29/345,580, filed on Oct. 19, 2009, now Pat. No. Des. 651,607.

CLAIM

The ornamental design for an electronic device, as shown and described.

DESCRIPTION

FIG. 1 is a front perspective view of an electronic device showing our new design;
 FIG. 2 is rear perspective view thereof;
 FIG. 3 is a front view thereof;
 FIG. 4 is a rear view thereof;
 FIG. 5 is a right side view thereof;
 FIG. 6 is a left side view thereof;
 FIG. 7 is a top view thereof;
 FIG. 8 is a bottom view thereof;
 FIG. 9 is an alternative bottom view thereof, with the stand removed for clarity of illustration;
 FIG. 10 is a front perspective view of a second embodiment thereof;
 FIG. 11 is rear perspective view thereof;
 FIG. 12 is a front view thereof;
 FIG. 13 is a rear view thereof;
 FIG. 14 is a right side view thereof;
 FIG. 15 is a left side view thereof;
 FIG. 16 is a top view thereof;
 FIG. 17 is a bottom view thereof; and,
 FIG. 18 is an alternative bottom view thereof with the stand removed for clarity of illustration.
 The broken lines shown in the drawings depict portions of the electronic device that form no part of the claimed design.
